UNITED STATES PATENT OFFICE.

HENRY A. WEIHHMAN, OF PHILADELPHIA, PENNSYLVANIA.

DESIGN FOR A BRUSH-BACK OR SIMILAR ARTICLE.

SPECIFICATION forming part of Design No. 25,568, dated June 2, 1896.

Application filed August 30, 1895. Serial No. 561,041. Term of patent 31 years.

To all whom it may concern:

Be it known that I, HENRY A. WEIHHMAN, a citizen of the United States, residing in the city and county of Philadelphia and State of Pennsylvania, have invented and produced a new and original Design for Brush-Backs or Similar Articles, of which the following is a specification, reference being had to the accompanying drawings, in which—

Figure 1 is a perspective view of a brush-back having my design applied. Fig. 2 shows the design applied to the back of a mirror.

The leading feature of the design consists of the ornamental scrolls symmetrically placed upon opposing quadrants of the back having pearl-shaped beading upon the opposing quadrants, between the quadrants carrying the said scrolls, the whole inclosing an unornamented central portion.

A is the unornamented center of the back. 20

B are the ornamental scroll-patterns.

C is the pearl-shaped beading. The beading-pattern C is attenuated from the middle toward the two ends, as shown.

Having now described my invention, what 25 I claim as new, and desire to secure by Letters Patent, is—

The design for the backs of brushes or similar articles substantially as shown and described. 30

In testimony whereof I have hereunto set my hand this 19th day of August, 1895.

HENRY A. WEIHHMAN.
